UNITED STATES PATENT OFFICE

CLARENCE SEFFENS AND JOHN R. ROBINSON, OF PARKERSBURG, WEST VIRGINIA

CHANGEABLE EXHIBITOR

Application filed August 7, 1928. Serial No. 298,009.

This invention relates to new and useful improvements in changeable exhibitors and has particular reference to that character of exhibitor adapted to be employed in conjunction with street cars, buses and the like and includes generally a casing having a transparent front wall the back of which is movable and indicating strips having various destination marks thereon visible through the transparent wall of the casing so that said markings may be readily viewed to inform those about to board the street car or bus as to the particular destination of the vehicle.

16 An object of this invention is to provide a device of this character which is very simple in its construction and inexpensive of manufacture and one that embodies but few parts to be so co-related as to reduce the possibility 20 of disarrangement to a minimum.

With the foregoing and other objects in view as the nature of the invention will be better understood, the same comprises the 25 novel form, combination and arrangement of parts hereinafter more fully described, shown in the accompanying drawings and claimed.

In the drawing wherein like reference characters indicate corresponding parts 30 throughout the several views:

Figure 1 is a front elevation of our improved exhibitor,

Figure 2 is a top plan view thereof,

Figure 3 is a detail longitudinal trans- 35 verse section,

Figure 4 is a longitudinal section taken at right angles to Figure 3,

Figure 5 is a rear elevational view,

Figures 6 and 7 are enlarged fragmentary 40 vertical sections taken substantially on the line 6—6 and 7—7 of Figure 3, and

Figure 8 is a perspective of one of the strip guide pins.

Now having particular reference to the 45 drawings, our novel exhibitor consists of an elongated casing 5 of suitable material open at its front side and provided at said open side with a pair of longitudinally spaced glass panels 6—6, the ends of the innermost 50 panel terminating slightly inwardly of the

end walls of the casing as more clearly illustrated in Figure 3.

Spacing strips *a*—*a* are secured to the top and bottom walls of the casing intermediate the adjacent longitudinal edges of the panels 55 6 for retaining these panels in spaced relation. Additional retaining strips *b* are likewise secured to the top and bottom walls of said casing in longitudinal spaced relation to the spacing strips *a* and between the corresponding strips *a* and *b* is received the upper and lower marginal edges respectively of the innermost transparent panel 6 as shown to advantage in Figure 7. As also shown in this figure, the strips *a* and panels 60 6 define a longitudinally extending guideway *c* in which guideway is movable an exhibitor strip 11, which strip 11 will be hereinafter described more in detail.

The rear wall of this casing 5 is provided with a suitable hinged door 7 so that access 70 may be had to the interior of said casing. Mounted vertically within this casing 5 adjacent the end walls thereof are roller shafts 8—8, the lower ends of which extend through the bottom wall of the casing and are constructed at said lower ends to provide suitable turning handles 9—9.

Secured to these pins are flanged belt rollers 10—10 while secured to these rollers at 80 the opposite ends of an indicating belt or strip 11 of predetermined length, said strip or belt being provided throughout its length with varied destination markings as disposed in Figure 1.

Preferably the strip or belt is of nontransparent material and the letters forming the various designations are of a transparent material so that light rays within the casing will project therethrough.

At the ends of the innermost glass panel 6 there is arranged vertically extending guide pins 12—12 over which the strip or belt is trained and passing between said panels 6—6 as clearly illustrated in Figure 3.

Obviously the arrangement of the strip or belt between these panels 6—6 will maintain the same in flat like condition so that the designation shown may be clearly viewed.

Mounted within the casing 5 in back of the 100

visible portion of the belt or strip are a plurality of electric lamps or illuminating means 13—13. Obviously by rotating the handles 9—9 of the roller shaft 8—8 the strip or belt 5 will be rolled from one roller on to the other causing the movement of the strip or belt between the panel 6—6 so that various indications may be brought to light between said glass panels.

10 In view of the foregoing description when considered in conjunction with the accompanying drawings it will be apparent that we have produced a highly novel, simple and extremely useful changeable exhibitor that is 15 well adapted for all of the purposes heretofore designated.

Even though we have herein shown and described the invention as consisting of certain detail structural elements, it is nevertheless to be understood that minor changes may 20 be made therein without affecting the spirit and scope of the appended claims.

Having thus described our invention, what we claim as new is:

25 1. In a changeable exhibitor, a casing having an open front and including top and bottom walls, a transparent panel closing said open front, spacing strips secured to the top and bottom walls engaging the inner face of 30 said transparent panel, a second transparent panel arranged in rear of the first mentioned panel and engaging said strips and terminating short of the ends of the first referred to panel, said strip and said panels defining 35 a longitudinally extending guideway, illuminating elements arranged within said casing, vertically disposed rollers mounted for rotation within said casing adjacent the opposite ends of said casing, means for rotating said 40 rollers, an exhibitor belt traversing said rollers, said belt being movable in said guideway and said belt having indicia characters formed thereon, said indicia characters being formed of transparent material.

45 2. In a changeable exhibitor, a casing open along one side thereof, a pair of spaced apart transparent panels arranged in said casing and closing said opened side, a pair of spaced apart strips arranged between said panels 50 and constituting with said panels adjacent said open side of the casing a guide passage, and an indicia carrying strip movable through said guide passage, said panels being of unequal length, and guide rollers for said 55 strip at opposite ends of said guide passage, their being one guide roller adjacent each end of said shorter of said panels.

In testimony whereof we affix our signatures.

CLARENCE SEFFENS.
JOHN R. ROBINSON.
